UNITED STATES PATENT OFFICE.

JOHN TAYLOR, OF SALT LAKE CITY, UTAH.

COAL-DUST FURNACE.

1,373,776.

Specification of Letters Patent.

Patented Apr. 5, 1921.

Application filed June 6, 1919. Serial No. 302,330.

To all whom it may concern.:

Be it known that I, JOHN TAYLOR, a citizen of the United States of America, residing at Salt Lake City, in the county of 5 Salt Lake and State of Utah, have invented certain new and useful Improvements in Coal-Dust Furnaces, of which the following is a specification.

This invention relates to coal dust furnaces adapted to burn fine fuel in suspension and it has for its object the provision of improved means for bringing about an intimate mixing of the fine fuel, such as coal dust with the necessary amount of air 10 to produce substantially perfect combustion, together with a combustion chamber of such shape and designed in such manner as to secure a highly efficient burning of the fuel.

Another object of the invention is to 20 provide an improved feeding means for feeding powdered coal dust or the like to a combustion chamber wherein means are provided for permitting the passage of 25 larger particles of the fuel past a fan without hitting the blades thereof.

It is intended that the air and coal dust discharged into the combustion chamber shall be ignited by the heat existing there- 30 in and by the incandescent condition of bricks constituting the walls thereof.

Further objects and advantages of the invention will be set forth in the detailed description which now follows.

In the accompanying drawings—

Figure 1 is a sectional view through the combustion chamber upon line 1—1 of Fig. 4, showing a stove or range to which the same is applied, in end elevation;

Fig. 2 is a side view of the blowing or feeding apparatus;

Fig. 3 is a sectional view upon line 3—3 of Fig. 2;

Fig. 4 is a horizontal sectional view 45 through the combustion chamber upon line 4—4 of Fig. 1;

Fig. 5 is a vertical sectional view upon line 5—5 of Fig. 4;

Fig. 6 is a plan view of the feeding ap- 50 paratus; and

Fig. 7 is a side elevation of the feeding apparatus with one of the plates removed.

Like numerals designate corresponding parts in all of the figures of the drawings.

Referring to the drawings 5 designates 55 a combustion chamber the front of which is closed by a door 6. This combustion chamber preferably has its inner walls formed of fire brick 7. The combustion chamber is preferably water-jacketed as in- 60 dicated at 8. A port 9' leads through the rear wall of the combustion chamber and communicates with a flue 9, through which the products of combustion from the com- 65 bustion chamber are discharged into and through the stove indicated at 10. 11 designates an oil tank from which oil may be fed through a pipe 12 to the interior of the combustion chamber for initially setting the device in operation. The lower part of the 70 flue 9 is provided with a plug-like closure 13 that is carried by a counter weighted lever 14, the latter being pivoted at 15 and this structure provides means for cleaning 75 out the ashes and clinker that may be pushed from the combustion chamber into the flue 9.

After the combustion chamber has been initially heated by oil introduced through the pipe 12 combustion therein is afterward maintained by a supply of air and 80 fine fuel, such as coal dust, fed into the combustion chamber tangentially through a pipe 16. This pipe is preferably water-jacketed as indicated at 17, both the water-jackets receiving their supply through pipes 85 18, 18^a and 18^b. An outlet pipe 18^c leads from water jacket 8.

19 designates a coal bin adapted to receive coal dust or other powdered or fine fuel. A slideable gate 20 is movable upon a 90 pipe 21 which projects into the coal bin and has an opening 22 formed in its side. The gate 20 is movable with respect to this opening in such manner as to control the amount of fuel passing therethrough. A worm con- 95 veyer 23 is disposed within the pipe 21 and feeds the fuel longitudinally therethrough and discharges the fuel through a nozzle or spout 24 into a fan casing 25. The air inlet opening for supplying air to the fan is in- 100 dicated at 21^a. The worm 23 receives its motion from a shaft 26 that is driven from a motor 27 by means of pulleys 28 and 29, belt 30, shaft 31, worm 32, and worm gear 33 the latter being fast upon the shaft 26. The 10 pulley 28 is mounted upon the shaft 34 of the motor and this shaft likewise carries the fan 35 that is disposed within the fan

casing 25. A discharge pipe 36 leading from this fan casing forms an extension of the pipe 16.

A funnel like member 37 is carried by a pipe 38 which projects at an angle from the pipe 36 in such manner as to cause air to be drawn thereinto by the force of the blast through the pipe 36. By the plan view of Fig. 6 it will be seen that the fan 10 casing is provided with a lateral extension 39 in which a channel is formed that lies in alinement with the nozzle 24 and to one side of the fan 35 which permits the larger particles of the fuel to pass the fan without 15 actually contacting with the fan blades. A washer 40 upon the shaft of the fan acts as a baffle to prevent the fuel from coming in direct contact with the fan.

It is to be noted that when the fuel first 20 enters the combustion chamber it enters at the forward part of said combustion chamber and is discharged into a lateral extension 41 of said combustion chamber which renders said combustion chamber of larger 25 diameter at the forward portion thereof than at the rear portion thereof. The result is that a whirling in a spiral path is set up, and the intimately mixed coal dust and air are brought into contact with heat and light 30 radiated from the incandescent walls of the combustion chamber and are ignited and burned.

As the coal dust is heavier than air most 35 of it would crowd against the lower side of pipe 16. To prevent such action I have placed a dent 16^a in pipe 16 near its mouth, thus throwing the coal dust in the direction indicated by dots Fig. 1, the air going in the course indicated by arrows as but little 40 of it would strike this dent.

The coal dust being heavier it would not turn and run tangent so quickly as the air but continues straight up and crosses into the path of heated air nearer the center of 45 combustion chamber where it ignites.

The structure herein shown and described

provides means for feeding and burning powdered fuel in suspension with the utmost efficiency and economy.

It is to be understood that the invention 50 is not limited to the precise construction set forth but that it includes within its purview whatever changes fairly come within the spirit of the appended claims.

Having described my invention what I 55 claim is—

1. In a device of the character described, a substantially circular combustion chamber the axis of which is horizontally disposed, a conductor for the products of combustion leading from the rear of said chamber and materially smaller in diameter than 60 said combustion chamber, a flue disposed at right angles to said conduit and a pipe adapted to carry air and powdered fuel, 65 said pipe leading through the side wall of the combustion chamber adjacent the front end thereof and discharging tangentially thereinto.

2. In a device of the character described 70 a substantially circular combustion chamber, the axis of which is horizontally disposed, a conduit for the products of combustion leading from the rear of said chamber and materially smaller in diameter than 75 said combustion chamber, a flue disposed at right angles to said conduit, a pipe of such size as to carry air and powdered fuel leading through the side walls of the combustion chamber adjacent the front end there- 80 of and discharging tangentially thereinto, and a raised element in said pipe adjacent its point of discharge and disposed at the bottom thereof to deflect the heavier part of the current upwardly at the moment of 85 discharge.

In testimony whereof I affix my signature in the presence of two witnesses.

JOHN TAYLOR.

Witnesses:

ROBERT L. JUDD,
I. M. FYFE.
